FLUID COMPRESSOR

Philip L. Crittenden, Edgewood, Pa., assignor to
The Westinghouse Air Brake Company, Wil-
merding, Pa., a corporation of Pennsylvania

Application January 31, 1935, Serial No. 4,263

4 Claims. (Cl. 230—212)

This invention relates to a fluid compressor and more particularly to an improved air compressor of the liquid cooled type having unloading means associated with the suction valves for 5 the compressor cylinders.

Liquid cooled air compressors are in use at the present time, but these are not entirely satisfactory as in these compressors, it is not possible to carry away the heat created by the compression of the air in the cylinders fast enough to properly cool the cylinders. In addition, in the compressors now in use which are provided with unloading means to hold the suction valve open, it has been difficult to remove and replace 10 the suction valves when it is necessary to service these units.

It is an object of this invention, therefore, to provide an improved compressor incorporating means to insure proper cooling of the cylinder 20 walls.

A further object of the invention is to provide a compressor incorporating unloading means comprising means to maintain the suction valve open, the suction valve and unloading means being constructed so that it can be readily removed and replaced.

A further object of the invention is to provide an improved air compressor.

Other objects of the invention and features of 30 novelty will be apparent from the following description taken in connection with the accompanying drawings, in which.

Figure 1 is a side elevational view of one embodiment of the improved compressor provided 35 by my invention;

Figure 2 is an end elevational view of the compressor shown in Figure 1;

Figure 3 is a sectional view taken substantially along the line 3—3 of Figure 2 with portions shown in elevation;

Figure 4 is a sectional view taken substantially along the line 4—4 of Figure 3;

Figure 5 is a sectional view taken substantially along the line 5—5 of Figure 3; and

Figure 6 is a fragmentary sectional view taken substantially along the line 6—6 of Figure 5.

Referring now to the drawings, the compressor therein illustrated has a cylinder casting indicated generally by the reference character 10 and which may be of any suitable construction.

As illustrated, the cylinder casting 10 has the crankcase formed integral therewith, and, in addition, has the cylinders 11 formed therein, in 50 which are reciprocable the pistons 12 which are

mounted on connecting rods 13 having their lower ends secured to the throws 14 of the crank-shaft 15 which is rotatably supported on bearings secured in the cylinder body 10. A jacket 16 is formed around the cylinders 11 so as to 5 provide a chamber 19 surrounding the cylinders and adapted to hold a quantity of a suitable cooling medium such as water.

As is best shown in Figs. 3 and 4 of the drawings, the cylinders 11 are each provided with a 10 plurality of axially extending ribs or fins 20 which project into the chamber 19 which is adapted to hold the cooling medium. Because 15 of the large surface area of the fins 20 there is a large heat radiated surface for each of the cylinders 11, and the heat which is generated in the cylinders as a result of the compression of the fluid in these cylinders may be carried through the cylinder wall and transferred to the 20 cooling medium in the chamber 19.

In the preferred construction the fins 20 which 25 project from the cylinders 11 into the chamber 19 extend axially of the cylinders substantially the entire length of the cylinders and project from the cylinders in planes which are substantially perpendicular to the plane in which the cylinders are disposed. In addition, the fins on each cylinder which are adjacent a plane perpendicular to the plane in which the cylinders are arranged and which extends through the center of the cylinder, project from the cylinder a smaller distance than the fins which are remote from this plane. This arrangement of the fins permits the cylinders 11 to be placed somewhat closer together than is possible with radially extending fins and at the same time insures that the cylinders will be adequately and uniformly cooled throughout their entire circumference as the heat dissipating capacity of the individual fins is increased in those portions of the cylinders in which the circumferential spacing of the fins is increased.

The compressor has a detachable cylinder head 25 secured over the tops of the cylinders 11 by means of the bolts 26. The cylinder head 25 has chambers therein extending through the cylinder head, and including a chamber indicated at 30, and adapted to contain the exhaust valve assembly indicated generally by the reference character 31. The chambers 30 each extend over a portion of one of the cylinders 11, as is best shown in Figure 5 of the drawings. Similar chambers 30 are provided for each of the two cylinders in the compressor shown in the draw- 50 55

ings, and these communicate with a manifold formed in the cylinder head and indicated at 34. A discharge pipe 35 leads from the manifold 34 to carry away the fluid compressed by the compressor.

Inlet chambers 40 adapted to receive the inlet valve assemblies indicated generally by the reference character 41, are also formed in the cylinder head 25 and each of these chambers extends over a portion of one of the cylinders 11 and the chambers communicate with the manifold 44 which is supplied with air from the inlet pipe 45. The head 25 is provided with a jacket 48 extending around the chambers 39 and 40 and the manifolds 34 and 44 and forming a chamber around these portions adapted to contain a quantity of cooling liquid. A pipe 49 is connected to the head 25 to carry away the fluid which passes through the chamber in the cylinder head.

The construction of the valves employed in the compressor provided by my invention is best shown in Figure 6 of the drawings, where it will be seen that the exhaust valve assembly 31 comprises a seat element 60 adapted to rest upon a shoulder 61 formed in the cylinder head. The seat element 60 contains a plurality of ports 62 arranged in two annular series and adapted to be closed by the annular valve members 63 and 64 which are normally held in the closed position by means of springs 65 which are seated in a spring retainer cage 68. The spring retainer cage 68 and the valve seat 60 are held in place by means of a spider or cage indicated generally by the reference character 70, and which is securely held by means of a clamp or plate 71 which is bolted to the top of the cylinder head, and which has the adjusting screw 72 threaded therein and engaging the spider 70 to press it downwardly to hold the members 60 and 68 in place. When it is desired to remove the exhaust valve assembly for servicing or for other purposes it is necessary only to remove the clamp or plate 71. This permits the exhaust valve assembly to be lifted out of the chamber 30.

The inlet valve assembly 41 is generally similar in construction to the exhaust valve assembly 31, and as shown in Figure 6 of the drawings, it is arranged in the chamber 40 in the cylinder head and comprises a spring retaining cage 80 seating on an annular shoulder 81 adjacent the lower end of the chamber 40. A valve seat 83 is positioned above the cage 80 and has a plurality of passages 84 extending therethrough and arranged in two annular series. A pair of annular valve members 85 and 86 are positioned between the spring retaining cage 80 and the valve seat 83 and are normally urged against the seat 83 so as to close the passages 84 by the springs 87 which are held by the retaining cage 80.

The spring retaining cage 80 and the valve seat 83 are held in position by means of the spider or framework indicated generally by the reference character 90 and comprising an annular peripheral portion 91 and a plurality of diverging arms 92 which extend upwardly and inwardly from the annular peripheral portion 91 and merge into a central portion in which is formed a cylinder 95 which is open at the lower end. A piston 96 is positioned in the cylinder 95 and is reciprocable therein and has secured to the lower face thereof a plurality of fingers 98 and 99 which extend into the valve ports 84 so that when the piston 96 is moved downwardly the fingers 98 and 99 engage the valve members 85 and 86 to press them away

from their seats in the valve seat 83 and thereby hold the inlet valve open. A spring 100 is positioned between the piston 96 and the valve seat 83 and normally urges the piston 96 upwardly so that the fingers 98 and 99 do not engage the valve members 85 and 86.

The cylinder 95 has a wall 105 extending across the upper end thereof and this wall has a passage 106 extending therethrough. An annular gasket 107 is secured in a groove in the upper face of the wall 105 and is engaged by the clamp or cover plate 110 which is secured on the top of the cylinder head. The gasket 107 is preferably constructed of resilient material, such as rubber, so that it will effectively seal the area around the top of the cylinder 95 even though the distance between the upper end of the cylinder 95 and the lower face of the clamp or cover plate 110 varies somewhat in different installations. The clamp or cover plate 110 has an adjusting screw 112 threaded therein and engaging the central portion of the wall 105 so as to press the cage 90 downwardly to hold the spring retaining cage 80 and the valve seat 83 securely in place.

In addition the plate 110 has a passage 115 formed therein and communicating with the chamber defined by the annular gasket 107 and with a similar passage 116 formed in the cylinder head 25. If desired, a bushing 117 may be fitted around the passage and extend across the joint between the cover plate 110 and the cylinder head 25 to prevent the escape of the fluid through the joint between these members.

When fluid under pressure from any suitable source is supplied to the passage 116 it flows through this passage to the passage 115 and therefrom to the passage 106 through the wall 105 to the upper end of the cylinder 95 and exerts a pressure on the piston 96 forcing the piston downwardly against the spring 100 so that the fingers 98 and 99 press against the valve members 85 and 86 to hold them in the open or unloading position. When the pressure of the fluid in the cylinder 95 is released the spring 100 returns the piston 96 to its upper position and allows the inlet valve to again be closed by the springs 87.

When it is desired to remove the inlet valve assemblies for servicing or for other purposes it is necessary only to remove the plate 110 which is accomplished very readily. The inlet valve assemblies can then be lifted out through the opening uncovered by the plate 110.

From the foregoing it will be seen that the improved compressor provided by my invention has means to insure proper cooling of the cylinder walls.

It will also be seen that the improved compressor provided by my invention has an inlet valve incorporating unloading means and that this valve is constructed so that it can be readily removed and replaced for service or for other purposes.

While one embodiment of the improved compressor provided by my invention has been illustrated and described in detail, it should be understood that the invention is not limited to these details of construction but that numerous changes and modifications may be made without departing from the scope of the following claims.

Having now described my invention, what I claim as new and desire to secure by Letters Patent, is:

1. In a fluid compressor, in combination, a body comprising a unitary casting having a cylinder portion having a bore extending therethrough and

adapted to receive a piston, a jacket surrounding a portion of the cylinder portion and forming a chamber adapted to contain a cooling liquid, fins formed integral with said cylinder portion and extending into said chamber, the fins extending axially of the cylinder portion and projecting from the cylinder portion in substantially parallel planes.

5. In a fluid compressor, in combination, a body comprising a unitary casting having a cylinder portion having a bore extending therethrough and adapted to receive a piston, a jacket surrounding a portion of the cylinder portion and forming a chamber adapted to contain a cooling liquid, fins formed integral with said cylinder portion and extending into said chamber, the fins extending axially of the cylinder portion and projecting from the cylinder portion in substantially parallel planes, the fins on the said cylinder portion adjacent a plane of the center of the cylinder projecting from the cylinder portion a distance less than the fins remote from said plane.

10. In a fluid compressor, in combination, a body comprising a unitary casting having a plurality of cylinder portions each having a bore therein and adapted to receive a piston, a jacket surrounding a portion of the said cylinder portions and forming a chamber adapted to contain a cooling liquid, fins formed on said cylinder portions and extending into said chamber, the fins extending axially of the cylinder portions and projecting therefrom in substantially parallel planes.

15. In a fluid compressor, in combination, a body comprising a unitary casting having a plurality of cylinder portions each having a bore therein and adapted to receive a piston, a jacket surrounding a portion of the said cylinder portions and forming a chamber adapted to contain a cooling liquid, fins formed on said cylinder portions and extending into said chamber, the fins extending axially of the cylinder portions and projecting therefrom in substantially parallel planes.

20. In a fluid compressor, in combination, a body comprising a unitary casting having a plurality of cylinder portions each having a bore therein and adapted to receive a piston, a jacket surrounding a portion of the said cylinder portions and forming a chamber adapted to contain a cooling liquid, fins formed on said cylinder portions and extending into said chamber, the fins extending axially of the cylinder portions and projecting therefrom in substantially parallel planes, the fins on each of said cylinder portions adjacent a plane perpendicular to the plane in which the cylinder portions are disposed and extending through the center line of the said cylinder bore projecting from the cylinder portion a distance less than the fins remote from said plane.

25. PHILIP L. CRITTENDEN.
